DESIGN FOR A GLOVE

Joseph F. Ward and Michael Wascoe, Allentown, Pa., assignors to Queen City Textile Corporation, Allentown, Pa., a corporation of Pennsylvania

Application September 5, 1940, Serial No. 94,814

Term of patent 14 years

To all whom it may concern:

Be it known that we, Joseph F. Ward and Michael Wascoe, citizens of the United States, residing at Allentown, in the county of Lehigh and State of Pennsylvania, have invented a new, original, and ornamental Design for a Glove, of which the following is a specification, reference being had to the accompanying drawing, forming part hereof.

The characteristic feature of our design resides in the glove disclosed having the specific stitching applied as shown.

We claim:

The ornamental design for a glove, as shown and described.

JOSEPH F. WARD.
MICHAEL WASCOE.
